UNITED STATES PATENT OFFICE

126,570

DESIGN FOR A GAME BOARD

Hubert McKinley Pallett, Kansas City, Mo.

Application January 30, 1941, Serial No. 98,556

Term of patent 14 years

To all whom it may concern:

Be it known that I, Hubert McKinley Pallett, a citizen of the United States, residing at Kansas City, in the county of Jackson and State of Missouri, have invented a new, original, and ornamental Design for a Game Board, of which the following is a specification, reference being had to the accompanying drawing, forming part thereof.

I claim:

The ornamental design for a game board, as shown.

HUBERT MCKINLEY PALLETT.
